RECIPROCATING MOTOR

Karl Gustaf Östberg, Stockholm, Sweden, assignor to Fabriksaktiebolaget Haldatxametern, Halmstad, Sweden, a company of Sweden

Application July 18, 1939, Serial No. 285,210
In Sweden July 28, 1938

5 Claims. (Cl. 121—164)

The present invention relates to driving mechanisms for machines or the like having an intermittent or reciprocatory movement, such as plate shearing machines, nibbling machines, presses, 5 punching machines, forging hammers or the like. More particularly the invention relates to driving mechanisms of the kind set forth which comprise a cylinder having an inlet and an outlet for a pressure medium, a piston movable in said cylinder, and a valve for controlling said outlet, said valve being adapted to be held in closed position by the pressure in the cylinder and to be moved to open position by the piston during its return movement.

15. It is an object of the invention to provide an improved driving mechanism of said kind which is simple of construction and efficient and reliable of operation. With said and other objects in view a driving mechanism has been provided according to the present invention in which said controlling valve is coupled with the cylinder so that the valve is opened by the piston striking against an abutment on the valve at the end of the stroke and is restored to closed position by 25 the piston during the return movement of the latter, for instance under the action of an auxiliary force, by way of example by spring power. The driving medium advantageously consists of oil or some other liquid preferably driven to the cylinder by means of a continuously operating compressor or the like, a practically constant stream of liquid being then supplied to the cylinder at the inlet side. The operating speed then becomes approximately inversely proportional to the 35 length of the stroke which preferably is adjustable.

The invention will now be described more in detail having reference to the drawings attached to this specification and forming part thereof. In 40 the drawings, which show an embodiment adapted more particularly to be used in plate shearing machines or the like, Figure 1 is a side view and partly a vertical section of the mechanism, and Figure 2 a front view.

45. The cylinder 1 is carried by a frame 2 and provided with a detachable cover 3 which is secured to the cylinder by means of screws and secured also directly to the frame. Movable in the cylinder 1 is a ring-shaped piston 4 which rests loosely on a circular plate 5 forming the upper extended end of a hollow piston rod 6, which passes through a lining 7 provided in the cylinder cover 3, said hollow piston rod carrying at its lower end a square holder 8 for one cutting tool 9 of a plate 50 shears the other cutting tool 10 of which is insert-

ed in a lower cutting tool holder 11 which is rigidly secured in the frame 2. The piston rod is effectively guided by the movable cutting tool holder 8 engaging with a guide 12 provided in the frame. 5

In the present embodiment the driving mechanism is assumed to be hydraulically operated, oil being preferably used as a pressure medium, said oil being preferably driven in a closed circuit by a continuously operating compressor or the like. 10 and being supplied to the cylinder at the inlet 13 and returned to the compressor through the outlet 14. The outlet is controlled by a valve 15 which is coaxial with the piston, the lower cylindrical portion of said valve fitting into the ring-shaped piston 4 so that the valve will be movable axially with respect to the piston. Secured by means of screws to the upper side of the piston is a ring 16 the inner edge of which overhangs an annular flange 17 on the valve 15. The ring-shaped space immediately below the flange 17 is filled with pressure medium, so that when occupying its closed position, as shown in Figure 1, the valve is held forcefully pressed against its conical valve seat 18 because of the fluid pressure 15 on the underside of the flange 17. 20

Figure 1 shows the various parts of the driving mechanism in the positions which they occupy when the piston is prepared to begin its downward stroke under the action of the hydraulic pressure 30 acting on its upper side. In this position of the parts the underside of the valve 15 is engaged by a circular plate 19 which by means of a helical spring 20 disposed within the piston rod 6 is held pressed against six spacing pins 21 passing freely 35 through corresponding holes in the plate-shaped upper part 5 of the piston rod and resting at their lower ends on a nut 22 which is threaded on to the piston rod. With the underside of the nut engages the upper end of a powerful helical spring 40 23 which at its lower end engages with a ring 24 that rests on balls 25 at the bottom of the cylinder cover 3. A ring 26, which is threaded over the piston rod 6 and which is held in position on the piston rod by means of a cross pin, serves to prevent an unintentional unscrewing of the nut 22. 45

Around its circumference the nut is provided with a number of teeth which engage with a pinion 28 journalled on a bolt 27 between the cylinder and the cover, said pinion being provided with a 50 radially extending handle 29. By moving the handle towards the one or the other side, the nut 22 can be turned on the piston rod, thereby adjusting the piston and the plate 19 axially with respect to the valve 15 for the purpose of chang- 55

ing the length of stroke which, as will be clear from the following, is equal to the distance between the lower surface of the ring 16 and the upper surface of the flange 17 in the illustrated position.

In front of the cylinder there is provided between the inlet 13 and the outlet 14 a by-pass 30 for the pressure medium which by-pass, when the driving mechanism is in operation, is kept closed by a starting and safety valve 31. Said valve is loaded with a powerful helical spring 32 disposed in a turnable tube 33 at the top of the cylinder and arranged under tension between the bottom of the tube and a movable cover 34 which during operation, as is shown in Figure 1, is held depressed by one edge of a cylinder 35 part of which is cut away along a plane that is parallel with its axis, said cylinder being journaled cross-wise in the upper part of the tube 33 and being provided with a bent starting rod 36. On account of the turnability of the tube 33 the starting rod 36 can be shifted to different lateral positions.

In the fluid passage between the valve 15 and the outlet 14 there is furthermore inserted a lifting valve 37 which is loaded by a comparatively weak spring, said valve serving only to increase the pressure on the upper side of the main valve 15 upon the opening of said valve in order thereby to accelerate the complete opening of the valve. Generally there is produced at the same time, however, on account of the acceleration of the body of liquid in the return conduit leading to the compressor, a sufficient counterpressure so that in most cases the auxiliary valve 37 is unnecessary and may be dispensed with.

The mechanism operates in the following manner.

As soon as the main valve 15 has been closed by the piston during the upward movement of the same caused by the spring 23, the piston immediately starts its down-stroke under the action of the high hydraulic pressure produced upon the closing of the valve. The movement of the piston continues until the ring 16 strikes against the flange 17 of the valve 15, opening said valve, the piston then stopping on account of the lowering of the pressure, whereas on account of the increased pressure on its upper side the valve will be flung down against the plate 19 connected with the piston. The pressure on the upper side of the piston is then further reduced and the piston is lifted by the spring 23, the piston then bringing along the valve 15. At the end of the stroke of the piston the closing of the valve will be accelerated because of the suction from the liquid flowing back through the return conduit. The operation is then repeated in the same manner. The driving mechanism is stopped by pulling down the starting rod 36, the starting valve 31 being then opened, offering a free passage for the pressure medium past the cylinder.

As will be clear from the above the length of the stroke of the piston is determined by the size of the space between the ring 16 and the flange 17 when the piston occupies its uppermost position, the stroke being equal to the width of said space. It will thus be possible to regulate the length of stroke by raising or lowering the working piston with respect to the valve 15 when in closed position by means of the regulating mechanism described, consisting of the spacing pins 21, the nut 22, and the pinion 28 provided with the handle 29. If the flow of liquid to the inlet 13 is constant the number of strokes per second will be approximately inversely proportional to the

length of stroke, as already mentioned. The space below the piston 4 is in communication with the atmosphere.

I claim:

1. A reciprocating motor comprising in combination, a cylinder provided at one end with an inlet for pressure medium and with an outlet arranged coaxially with respect to the cylinder, a piston movable in said cylinder, a valve body for controlling said outlet journalled coaxially in a central recess of said piston so as to be movable axially with respect thereto, an abutment on the piston restricting the axial movement of the valve body relatively to the piston in one direction, a stop member connected with the piston and shiftable in axial direction, said stop member serving to restrict said relative axial movement in the other direction, and means tending to move the piston towards the outlet end of the cylinder into a position in which the outlet is closed by said valve body and the length of stroke of the piston being substantially equal to the length of axial movement of the valve body relatively to the piston and being variable by adjustment of said shiftable stop member.

2. A reciprocating motor comprising in combination, a cylinder provided at one end with an inlet for pressure medium and with an outlet arranged coaxially with respect to the cylinder, a piston movable in said cylinder, a valve body for controlling said outlet journalled coaxially in a central recess of said piston so as to be movable axially with respect thereto, an abutment on the piston restricting the outward axial movement of the valve body relatively to the piston, spacing members passing freely through the bottom of said recess in the piston, an annular stop member mounted on the piston rod and adjustable in axial direction thereon, means keeping the outer ends of said spacing members in contact with said annular stop member, said spacing members and said annular stop member cooperating to determine the bottom position of the valve body in said central recess, and means tending to move the piston towards the outlet end of the cylinder into a position in which the outlet is closed by said valve body and the length of stroke of the piston being substantially equal to the length of axial movement of the valve body relatively to the piston and being variable by adjustment of said shiftable stop member.

3. A reciprocating motor as claimed in claim 2, in which said adjustable annular stop member consists of a nut threaded onto the piston rod and provided at its circumference with teeth engaging a pinion.

4. A reciprocating motor comprising in combination, a cylinder provided at one end with an inlet for pressure medium and with an outlet arranged coaxially with respect to the cylinder, a continuously operating compressor driving a constant stream of pressure medium to the cylinder, a by-pass provided in parallel with the passage through said outlet, a valve normally closing said by-pass, means for operating said by-pass valve, a piston movable in said cylinder, a valve body for controlling said outlet journalled coaxially in a central recess of said piston so as to be movable axially with respect thereto, an abutment on the piston restricting the axial movement of the valve body relatively to the piston in one direction, a second abutment restricting said relative axial movement in the other direction, means tending to move the piston towards the outlet end of the cylinder into a posi-

tion in which the outlet is closed by said valve body and the length of stroke of the piston being substantially equal to the length of axial movement of the valve body relatively to the piston and being variable by adjustment of said shift-
5 able stop member.

5. A reciprocating motor as claimed in claim 4,

in which said by-pass valve is loaded with a spring tensioned between said valve and a support which is shiftable so that the valve can serve simultaneously as a safety valve and a starting valve.

KARL GUSTAF ÖSTBERG.
